(57) **CLAIM**

The ornamental design for a guitar neck, as shown and described.

DESCRIPTION

FIG. 1 is a top perspective view of a guitar neck showing the first embodiment of my new design;

FIG. 2 is a bottom perspective view thereof;

FIG. 3 is a top view of thereof;

FIG. 4 is a bottom view of thereof;

FIG. 5 is a front view of thereof;

FIG. 6 is a back view of thereof;

FIG. 7 is a right side view of thereof;

FIG. 8 is a left side view of thereof;

FIG. 9 is a top perspective view of a guitar neck showing the second embodiment of my new design;

FIG. 10 is a bottom perspective view of thereof;

FIG. 11 is a top view of thereof;

FIG. 12 is a bottom view of thereof;

FIG. 13 is a front view of thereof;

FIG. 14 is a back view of thereof;

FIG. 15 is a right side view of thereof; and,

FIG. 16 is a left side view of thereof.

In the second embodiment, FIGS. 9-16, the stippling represents contrasting surfaces unlimited by colors.

The broken lines represent the portions of the guitar neck which form no part of the claimed design.
